CLAIM

The ornamental design for a pet bowl stand, as shown and described.

DESCRIPTION

FIG. 1 is a first perspective view of a pet bowl stand showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the pet bowl stand depicted in use with bowls.

The broken line showing of bowls in FIG. 9 is for illustrative purposes only and forms no part of the design claim.
